WELL TESTER

Granville A. Humason and Walter J. Clay,
Houston, Tex.

Application February 4, 1938, Serial No. 188,625

8 Claims. (CL 166—1)

The invention relates to a well sampling device for obtaining a sample of fluid at a desired level within an oil well, together with information of the temperature and pressure conditions 5 at the level of sampling.

An object of the invention is to provide a device of the class described having few working parts to get out of order and a device which is easy to construct and operate.

10 Another object is the provision of a device for obtaining uncontaminated fluid sample from within the well bore and at the same time will permit fluid to be pumped downwardly into the well to assist in releasing and lifting the device 15 from the well.

Another object is to provide a sample taking device in which the essential moving parts of the device are surrounded by a lubricant.

Still another object is the provision of a device for obtaining a sample in an oil well together with information of the maximum temperature and pressure at the level of sampling, the device being so constructed that the pressure indication will not be affected by pumping 25 pressure which may be applied after the sample has been taken.

Other objects together with the foregoing will be apparent from the following description taken in connection with the drawings in which:

30 Fig. 1 is a vertical section through the upper portion of the device of the invention.

Fig. 2 is a vertical section comprising a continuation of the view shown in Fig. 1.

35 Fig. 3 is a continuation of the view shown in Fig. 2 and shows the lower end of the device in position within a rat hole at the bottom of a well bore.

40 Figs. 4 and 5 are successive sectional views of the device showing the relative positions of parts when a sample is being taken.

Fig. 6 is an elevation partly in section comprising a continuation of the view shown in Fig. 5.

45 Fig. 7 is a sectional view of a maximum pressure gauge comprising an element of the invention.

Referring more particularly to the drawings the device is shown as connected to a tubing string 1 and comprising essentially a composite stem structure 2 surrounded by a tubular casing 3 having a rat hole packer 4 secured to the lower end thereof. A tubular extension 5 on the packer 4 is provided with perforations 6 whereby liquid 55 within the rat hole 7 at the bottom of a well

bore 8 may enter the axial bore 9 within the packer 4.

A head 15 at the upper end of the casing 3 is provided with a central opening 16 and upwardly extending jaws 17 which are adapted to cooperate with complementary jaws 18 on a coupling 19 which interconnects the tubing string 1 and the stem 2. A nipple 20 is threadedly connected to the lower end of the head 15 in a manner to provide an internal annular groove 10 21 to receive an annular flange 22 on a ring 23. This ring has upwardly and downwardly facing annular grooves 24 and 25 within which seal rings 26 and 27 are secured whereby a sealing unit generally designated as 28 is provided between the casing 3 and the stem 2.

A coupling 31 is attached to the lower end of the nipple 28 and has a reduced central section provided with threads 32 by means of which a releasable connection is effected between the 20 casing 3 and the stem 2, as will be further described.

Tubular sections 35 and 36 extend downwardly from the coupling 31 and are interconnected by means of coupling 37 to provide an annular internal groove 38 whereby a sealing unit 39 similar to the sealing unit 28, above described, is fixed in spaced relation with the sealing unit 28.

The packer 4 is secured to the lower end of the casing 2 through a tubular section 40 connected to the casing structure just described by means of a special coupling 41. This coupling and the tubular section 40 likewise provide an internal annular groove 42 by means of which a third sealing unit 43 similar to that above described is secured within the annular space between the casing 3 and the stem 2. The coupling 41 has a central reduced cross section at 44 to serve a purpose that will be described.

The tubular section 40 of the casing 3 is threadably connected to the head 45 of the rat hole packer 4 which includes a downwardly extending mandrel 46 surrounded by packing discs 47 of decreasing diameter whereby a tapered packer is provided. The packing discs 47 are held in assembled relation by means of a flange nut 48 to which the tubular extension 5 is attached.

A threaded opening in the lower end of the 50 tubular extension 5 receives a plug 50 bearing a maximum temperature indicating device 51. It is believed obvious that with this construction the temperature indicating device 51 will provide an indication of the maximum temperature of 55

the fluid which enters the bore 8 through openings 6 in the extension 5.

The stem 2 passes through the opening 16 in the head 61 and has a special coupling 60 intermediate its ends. This coupling is provided with peripheral threads which are adapted to releasably engage the threads 32 on the coupling 31 whereby the stem 2 may be held in fixed relation with the casing 3.

10 The stem 2 terminates at its lower end in an enlarged head 61 having a packing ring 62 to seal between the head 61 and the reduced section 44 of the coupling 41. Vertical passage ways 63 about the axis of the head 61 permit movement of fluid downwardly through the head to a downwardly opening valve 65. This valve comprises a cage 66 within which a ball valve 67 is resiliently urged upwardly against a seat 69 by means of a spring 68. This construction 20 closes the passage into the stem 2 against inward flow of fluid. The tension on the spring 68 may be adjusted so that a valve will open downwardly when a predetermined pressure within the stem is reached.

25 The head 61 is also provided with an axial opening 76 into which a maximum pressure indicating device 75 is threadably secured. A radial port 77 connects the axial opening 75 with the periphery of the stem intermediate the sealing rings on the assembly 42 when the device is being lowered to sample taking position as shown in Figs. 1 to 3. A maximum pressure gauge of any type may be used, one of such gauges being illustrated in Fig. 7 as comprising a body 80 having therein a piston or plug 81 which is urged downwardly within the body by means of a spring 82 placed under compression by plug 83 screwed into the body 80. The piston 81 is provided with a stylus or other recording element 84 which is urged sidewardly under the influence of spring 85 to contact with the recording strip 86. By means of this construction a mark will be inscribed upon the strip 86 which can subsequently be removed, the height of the record produced upon the strip indicating the maximum pressure to which the gauge was subjected during the sample taking operation.

30 A plug 90 within the stem 2 divides the stem into upper and lower chambers 91 and 92. This plug is provided with longitudinal passages 93 about its axis so that fluid may flow from chamber 91 to chamber 92. An axial opening 89 in the plug 90 is threaded to receive the lower end of the sample tube 84 which extends upwardly 40 within the stem 2 and is provided with a relief valve 59 at its upper end. A radial opening 87 extends from the hole 89 to the exterior of the stem 2 and is provided with a removable plug 95 having an orifice 96 therein whereby liquid 45 may be admitted to the interior of the sample chamber 84 in a manner that will be further brought out in the description of the operation of the device.

35 The relief valve 59 comprises a cage 52 within which a ball valve 53 is engaged by a plug 54 urged downwardly by means of compression spring 55 adjustably positioned within the cage by the plug 56. The cage 52 is provided with a plurality of ears 57 extending radially therefrom 50 serving to keep the sample chamber centered within the stem 2.

40 It is to be noted that the device described may be of any desired length and that while the device is shown as provided with a rat hole packer for taking samples within the rat hole in the

bottom of a well bore, the invention is not confined thereto but the device may be provided with other types of packer or wall engaging devices to obtain a sample at any level within a well bore.

45 When using the construction illustrated, the device is lowered within the well bore until the packer 4 is seated within the rat hole 1 preliminary to the taking of a sample of liquid within the rat hole and below the packer. When the 10 device is so positioned the liquid within the rat hole contacts the maximum temperature indicating device 51 and sufficient time will elapse during the taking of a sample that the temperature indicator will reach the temperature of the 15 surrounding liquid.

50 In order to obtain an indication of bottom hole pressure and to obtain the desired sample of liquid, the tubing string 1 is rotated to release the threaded connection between the stem 2 and the casing 3. When this connection is released the stem is moved downwardly whereupon the sealing ring 62 will move from engagement between the head 61 and the coupling 41 and fluid under bottom hole pressure will be admitted to 25 the maximum pressure indicator 75. Continued downward movement of the stem 2 will cause the orificed plug 95 to move below the sealing unit 43 whereupon fluid will move upwardly 30 from within the rat hole into the sample chamber 30 orifice 96.

55 As is clearly shown in Fig. 4, when the device is actuated for taking a sample, the collar 19 on the tubing 1 moves downwardly until the 35 jaws 18 thereon engage the complementary jaws 17 on the upper end of the casing 3. Hence if necessary the entire unit may be rotated through the tubing 1 preliminary to lifting the device from sample taking position. Normally, however, the tubing string may be lifted without such rotation whereby the passage 77 to the pressure gauge 75 and the orifice 96 leading to the sample chamber 84 will be closed off from the well liquid as the stem 2 moves upwardly 45 within the casing 3 until the ring 62 makes sealing engagement within the reduced section 44. In order to release the device from its setting within the rat hole, suitable drilling fluid may be pumped downwardly through the tubing 50 string 1. It is to be noted that any pressure exerted by this pumping cannot affect the pressure reading on the gauge 75 since the passage 77 leading to the gauge is closed when the stem 2 is drawn upwardly within the surrounding 55 casing. Furthermore as the bottom hole temperature is higher than the temperature of fluid that will be pumped into the well, the reading of the maximum temperature indicating device 51 will not be changed by this procedure. 60

56 What is claimed is:

65 1. A sampling device for oil wells for connection between a packer and a string of pipe, comprising a stem attached to said string, a casing surrounding said stem, spaced seals between the stem and casing, a connection between the stem and casing releasable by operation of the string whereby the stem may move longitudinally of the casing, a separate receiving chamber and a maximum pressure indicator within said 70 stem, and an outwardly opening port through the stem from each said chamber and said indicator, whereby passages to the chamber and indicator are opened by downward movement of the stem within the casing. 75

2. A sampling device comprising a casing, a 5
5 packer on the lower end of said casing to seal
with the surrounding walls in a well bore, a tubing
string, a stem within said casing and con-
nected to the tubing string, spaced seals be-
tween said stem and casing to form a lubricant
chamber within the casing, a threaded connec-
tion between the stem and casing whereby the
stem may be released for movement longitudi-
nally of the casing, and a sample receiving
chamber within the stem and in spaced relation
10 with the walls thereof so that fluid may be
pumped downwardly past said chamber, said
chamber having an outwardly opening port
15 whereby a passage to the chamber is opened
when the stem is moved longitudinally of the
casing.
3. A sampling device comprising a casing, a
20 packer on said casing to seal with the sur-
rounding walls of a well bore, a stem within said
casing, spaced seals between said stem and cas-
ing, a releasable connection between the stem
25 and casing intermediate said seals, and a sep-
arate sample receiving chamber within said stem
so that fluid may be circulated downwardly past
said chamber, there being a passage from the
exterior of the stem to said chamber whereby
30 fluid is admitted to the chamber when the stem
is moved downwardly within the casing.
4. A well sampling device comprising a tubu-
35 lar casing, a stem movable longitudinally within
said casing, spaced sealing means between said
stem and casing, a sample chamber within said
stem, said chamber having a port adapted to be
valved to admit fluid thereto by movement of
30 the stem relative to the casing, and separate pas-
sages downwardly within said stem past the
chamber whereby circulating fluid may be
pumped downwardly through the stem.
5. A well sampling device comprising a tubing
40 string, a stem attached to the lower end of said
string, a casing surrounding said stem and re-

leasably connected thereto, spaced seals between
said stem and casing, a cylindrical sample cham-
ber within said stem, a second chamber within
the stem, a maximum pressure indicator in said
second chamber, and a port leading from each 5
said chamber and indicator to the exterior of
the stem between the seals whereby fluid is ad-
mitted to the chambers and admit fluid when
the stem is moved longitudinally of the casing.

6. A device of the class described comprising 10
a sample chamber, a stem surrounding said
chamber and in spaced relation therewith, there
being a passage from the interior of the chamber
to the exterior of the stem, a casing surrounding
15 said stem, a slideable connection between the
casing and stem, and seals between said stem
and casing above and below said passage.

7. In a device of the class described, a sample
chamber, a stem surrounding said chamber, a
20 passage from said chamber to the exterior of
said stem, a downwardly opening valve at the
lower end of the stem, a casing surrounding the
stem and releasably connected thereto so that
the stem may move longitudinally relative to
25 the casing and spaced seals between the stem
and casing whereby fluid may be admitted to
the sample chamber when the passage from the
chamber moves from between the seals.

8. A sampling device comprising a casing,
means for fixing the position of the casing with-
30 in a well bore, a stem movably mounted within
said casing, maximum temperature indicating
means mounted within said device, whereby the
maximum temperature of fluid surrounding the
device will be registered thereon, a sample cham-
35 ber within the stem, there being a passage
through the stem past said chamber, and means
for admitting fluid to said chamber after the
device is positioned within the well bore.
